UNITED STATES PATENT OFFICE

HUGH F. CAMERON, OF HONDO, TEXAS, ASSIGNOR OF THREE-FOURTHS TO EDDIE C. CAMERON AND GEORGE MUENNINK, SR., BOTH OF HONDO, TEXAS, AND JOE C. JOHNSON, OF THREE RIVERS, TEXAS

OIL WELL TESTER

Application filed May 24, 1930. Serial No. 455,409.

This invention relates to improvements in testing devices for use in connection with oil well drilling operations.

The primary object of the present invention is to provide a device for testing formations at various depths in oil wells, which is positive in operation and obtains samples of oil and other foreign matter.

Another object of the invention is to provide a tester having an improved form of valve element which is operable for opening or closing from the top of the well after the tester has been properly positioned in the bottom thereof. Still another object of the invention is to provide a tester of the above described character having a novel means for opening or closing the tester to permit a sample of the fluid in the lower part of the well to enter the device or to close the same after the fluid has entered, as the case may be.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a view in side elevation of the tool embodying the present invention showing the same in working position.

Figure 2 is a central longitudinal sectional view through the upper portion of the tool.

Figure 3 is a central longitudinal sectional view through the lower portion of the tool.

Figure 4 is a transverse sectional view taken on the line 4-4 of Figure 1.

Figure 5 is a sectional view taken on the line 5-5 of Figure 3.

Figure 6 is a sectional view taken on the line 6-6 of Figure 3.

Referring more particularly to the drawings wherein like numerals of reference indicate corresponding parts throughout the

several views, the numeral 1 indicates the lower portion of a well bore, at the lower end of which is formed the reduced bore 2 which is commonly known as the "rat hole."

The tester embodying the present invention comprises a tubular casing 3 into the lower end of which is threadably secured one end of a plug 4 through which is formed a passage 5. The lower end of this passage 5 is enlarged and threaded as indicated at 6.

Within the casing 3 there is secured upon the upper end of the plug 4 a bearing ring 7. Disposed within the casing 3 is an elongated tubular body 8 the lower end of which has secured thereto a bearing ring 9 which rests upon the bearing balls 10 which in turn rest upon the ring 7 carried by the plug 4. The lower end of the body 8, which as previously stated is tubular, has interior threads 11 cut thereinto in the manner shown. The upper end of the body 8 is reduced slightly forming a neck 12 which extends through the upper end of the body of the casing 3 and terminates in the exteriorly threaded upper portion or head 13. At the point where the lower end of the neck 12 starts the body 8 is formed to provide a surrounding shoulder 14 in which, at one point, is formed a slight depression 15. When the body 8 is in position in the casing 3 the shoulder 14 lies within the casing a slight distance below the upper end thereof and the casing is formed at a point in the plane occupied by the shoulder 14 to provide a boss 16 through which is formed transversely of the casing wall the passage 17. In the inner end of this passage 17 is a pin 18, the inner end of which is rounded in the manner shown and this pin is normally urged inwardly by the spring 19 which is held in place in the passage 17 by a screw 20.

Formed in the boss 16 at right angles to the bore 17 is a second bore 21. In the inner end of this bore is slidably positioned a pointed pin 22 which is forced inwardly by a spring 23, held in place by a set screw 24. This pin 22 engages in a recess formed in the side of the pin 18 and normally holds this pin 18 back against the tension of the spring 19, while the tool is being lowered into the well.

Surrounding the neck portion 12 of the

body 8 and bearing upon the shoulder 14 is a packing 25 which is secured in place by a collar 26 threaded into the upper end of the casing 3 in the manner shown. The threaded upper end or head 13 of the body 8 receives a coupling 27 which connects with the body the lower end of the drill stem 28.

Surrounding the plug body 4 and bearing against the lower end of the casing 3 is a washer 29. This washer has bearing thereagainst the upper end of an inverted cone 30 which, of course, surrounds the plug 4. A key 31 arranged in the side of the plug and extending longitudinally thereof maintains the cone against rotation. This cone, while it may be formed of a number of materials, is preferably made up of leather disks placed one upon the other.

Extending downwardly from the plug 4 is a tube 32 the upper end of which is threaded as indicated at 33 and engages in the threaded portion 6 of the plug passage 5. The lower end of this tube is closed but has a small aperture formed therethrough as indicated at 34 for the connection with the tube of a flush valve of any suitable type, the valve being here indicated by the numeral 35 and shown in dotted lines. At a point intermediate its ends the tube 32 has an aperture 36 formed through the wall thereof.

As is shown the threaded area of the tube 32 extends a substantial distance downwardly from the upper end of the tube. This threaded portion carries a nut 37 which forces upwardly against the lower end of the cone 30 a washer 38 which, as shown, loosely surrounds the tube 32. The cone 30 extends a slight distance below the lower end of the plug 4 so that, as will be apparent, the compression of the plug 30 between the washers 29 and 38 by the nut 37 can be effected. The threaded portion 33 of the tube may also have mounted thereon a screen (not shown) if it is found desirable to use such an article.

Extending longitudinally through the tool is a longitudinally shiftable inner tube 39, which at the point 40 substantially midway between its ends has a circumferential enlargement which is threaded as shown. This threaded portion 40 of the shiftable tube 39 engages the threads 11 in the body 8. The tube 39 extends upwardly beyond the upper end of the body 8 and extends downwardly nearly to the bottom of the outer tube 32. This tube 39 is of an exterior diameter to snugly position in the outer tube 32 so that a close contact will be maintained between the adjacent walls of the two tubes. At a point adjacent its lower end the tube 39 has an aperture 41 formed through the wall thereof which may be brought into registration with the aperture 36 in the outer tube for the taking of a sample from a well, as will be hereinafter described.

Upon its outer surface at a point prefer-

ably adjacent the lower end of the cone 30 the tube 39 has a longitudinally extending flattened portion 42 and this flattened portion is engaged by the inner end of the set screw 43 threaded through the wall of the surrounding outer tube 32.

As will be readily seen this screw 43 will prevent turning of the tube 39 in the tube 32 but will not interfere with the longitudinal movement of the inner tube.

In operation the tool is attached to the lower end of a drill stem in the manner shown and the body 8 is turned in order to shift the tube 39 to a position where the aperture 41 will be out of register with the aperture 36 in the tube 32 and the end of the pin 18 will be engaged in the notch 15 in the shoulder of the body. The tool is then lowered into the well bore until the portion below the cone 30 enters the "rat hole" 2 and the cone has been seated firmly against the upper edge of this hole so that the passage of matter from the main well bore downwardly into the "rat hole" will be prevented. The drill stem is then rotated by any suitable means and this will rotate the body 8 and force the pin 18 out of the notch 15. The pin 18 will then become locked in retracted position by the adjacent pin 22, in the manner previously described, and by continued rotation of the body through the medium of the drill stem the tube 39 will be shifted longitudinally until the apertures 36 and 41 have been brought into registration. The fluid contents of the "rat hole" will then, of course, flow through these registered apertures and enter the tube 39 as will be obvious. Continued rotation of the body 8 will then raise the tube 39 to the point where the aperture 41 in the wall thereof will move past the aperture 36 and thus close the interior of the tube against the entrance of further liquid and also prevent the escape of the liquid therein when the tool is raised from the position described. The tool may then be withdrawn from the drill hole and emptied of the sample of fluid taken therefrom.

From the foregoing description it will be readily seen that the tool embodying the present invention is of simple construction, having few moving parts and thus being unlikely to get out of order. At the same time, it is positive in operation and will not fail to perform the functions for which it is designed.

Having thus described my invention, what I claim is:

1. An oil well testing device, comprising a "rat hole" closing body adapted to be lowered into a well on the end of a drill stem, a rotary element connected to said body and adapted to be attached to the drill stem, a tubular body carried upon the lower end of said first mentioned body for extension into the "rat hole", and longitudinally shiftable means

within said tubular body having connection with said rotatable body whereby it may be shifted when the rotatable body is turned for the admission of fluid from the "rat hole" into the tubular body.

2. An oil well tester, comprising a cone body designed to close the upper end of a "rat hole", an apertured sample receiving tube carried by said cone body, a longitudinally reciprocable tubular body extending into said first tubular body and having an aperture registerable with the aperture of the first tubular body, and means adapted to be connected with a supporting drill stem whereby upon rotation of the drill stem said second tubular body will be shifted longitudinally.

3. An oil well tester, comprising a cone body designed to close the upper end of a "rat hole", an apertured sample receiving tube carried by said cone body, a longitudinally reciprocable tubular body extending into said first tubular body and having an aperture registerable with the aperture of the first tubular body, and a rotatable element coupled with said cone having threaded connection with said last mentioned tubular body whereby upon rotation the second tubular body will be shifted longitudinally through the tool, said rotatable body being adapted for connection with a drill stem.

4. An oil well tester, comprising a plug for closing the top of a "rat hole" formed at the bottom of a well bore, an elongated tubular body closed at one end and attached at the other end to said plug for extension into the "rat hole", said body having an aperture through the wall thereof, an elongated tube extending through said plug into and snugly fitting in said body, said tube having an aperture in the wall thereof designed to register with the aperture in the encasing body, an element connected to the plug for coupling the tool to a drill stem, and means connecting said element with said tube whereby rotation of the element will shift said tube longitudinally in the tool.

5. An oil well tester, comprising a "rat hole" closing plug having a passage therethrough, a tube having one end closed and having its other end secured in said plug passage to extend into said hole, a tubular member connected to said plug and mounted for rotation, said member being designed for connection with a drill stem, a second tube having one end snugly reciprocably fitted into said first tube and extending through said member, and means coupling said member and said second tube whereby rotation of the member will cause longitudinal movement of the second tube and relative movement between registerable apertures in the walls of the tubes.

6. An oil well testing device, comprising a cone body adapted to close the upper end of a "rat hole" formed at the bottom of a well

bore, a body in said cone having a longitudinal passage therethrough, a casing connected to said body, a rotatable body within said casing and projecting beyond the upper end thereof, said rotatable body being adapted for connection to a drill stem, a tube closed at one end and having its other end connected to said first mentioned body, said tube having an aperture through the wall thereof, an inner tube having one end extended into said first tube and extending longitudinally through said rotatable body, and a threaded connection between said inner tube and said rotatable body whereby upon rotation of the rotatable body the inner tube will be moved longitudinally to shift an aperture in the wall thereof relative to the aperture in the first mentioned tube.

7. An oil well testing device, comprising a cone body adapted to close the upper end of a "rat hole" formed at the bottom of a well bore, a body in said cone having a longitudinal passage therethrough, a casing connected to said body, a rotatable body within said casing and projecting beyond the upper end thereof, said rotatable body being adapted for connection to a drill stem, a tube closed at one end and having its other end connected to said first mentioned body, said tube having an aperture through the wall thereof, an inner tube having one end extended into said first tube and extending longitudinally through said rotatable body, a threaded connection between said inner tube and said rotatable body whereby upon rotation of the rotatable body the inner tube will be moved longitudinally to shift an aperture in the wall thereof relative to the aperture in the first mentioned tube, and yieldable means normally restraining said casing and the rotatable body therein against relative movement.

8. In a well tester of the character described, a "rat hole" closing plug having a passage longitudinally therethrough, a tubular casing connected at one end to said plug, a rotatable body within said casing having a portion extending beyond the upper end of the casing and further having a surrounding shoulder disposed in the casing adjacent the upper end thereof, said shoulder having a recess in the face thereof, a spring pressed member carried by the casing and adapted to engage in said recess, said member being yieldable upon the application of rotary force to the body while the casing is being held, means for maintaining said member in retracted position after movement of said rotatable body, a sample receiver carried by the plug for extension into the "rat hole", and means operable upon rotation of said body for admitting a sample to said receiver.

9. An oil well tester, comprising a "rat hole" closing cone, a body carried by said cone and having a passage formed therethrough, a cylindrical casing carried by said body and

extending upwardly from said cone, a tube closed at one end and having its other end detachably connected to said body and extending downwardly from said cone, said cone 5 being interposed between a pair of plates one engaging the lower end of said casing, the other surrounding said tube and being forced upwardly by a nut threaded on said tube, a rotatable body in said casing having its upper 10 end extending beyond the upper end of the casing, an anti-friction bearing between said rotatable body and said first body, an elongated inner tube extending longitudinally through said rotatable body and projecting 15 downwardly into said first tube, said tubes having apertures in the walls thereof adapted to be brought into registration one with the other, a threaded connection between said inner tube and said rotatable body, and means 20 holding said inner tube against rotation, said rotatable body having its upper end formed for connection with the lower end of a drill stem.

10. An oil well tester, comprising a "rat 25 hole" closing cone, a body carried by said cone and having a passage formed therethrough, a cylindrical casing carried by said body and extending upwardly from said cone, a tube closed at one end and having its other 30 end detachably connected to said body and extending downwardly from said cone, said cone being interposed between a pair of plates one engaging the lower end of the casing, the other surrounding said tube and being forced 35 upwardly by a nut threaded on said tube, a rotatable body in said casing having its upper end extending beyond the upper end of the casing, an anti-friction bearing between said rotatable body and said first body, an 40 elongated inner tube extending longitudinally through said rotatable body and projecting downwardly into said first tube, said tubes having apertures in the walls thereof adapted to be brought into registration one 45 with the other, a threaded connection between said inner tube and said rotatable body, means holding said inner tube against rotation, said rotatable body having its upper end formed for connection with the lower end of a drill 50 stem, and yieldable means for coupling said rotatable body and said casing together.

In testimony whereof I hereunto affix my signature.

HUGH F. CAMERON.
